DESIGN FOR A COIN DISPENSING MACHINE

Raymond A. Leach, Los Angeles, Calif.

Application April 5, 1948, Serial No. 145,527

Term of patent 3½ years

(Cl. D52—3)

To all whom it may concern:

Be it known that I, Raymond A. Leach, a citizen of the United States, residing in the city and county of Los Angeles, and State of California, have invented a new, original, and ornamental Design for a Coin Dispensing Machine, of which the following is a specification, reference being had to the accompanying drawing, forming part thereof.

Fig. 1 is a front perspective view of a coin dispensing machine, showing my new design.

Fig. 2 is a left side elevation thereof, and

Fig. 3 is a top plan view.

I claim:

The ornamental design for a coin dispensing machine, substantially as shown.

RAYMOND A. LEACH.
